US0D1108752S

(12) **United States Design Patent** (10) Patent No.: **US D1,108,752 S**
(45) Date of Patent: ** Jan. 6, 2026

(54) **ROBOTIC CLEANER**

(71) Applicant: **Anker Innovations Technology Co., Ltd.**, Changsha (CN)

(72) Inventors: **Jaewan Jeong**, Shenzhen (CN); **Siyoon Kim**, Shenzhen (CN); **Ang Chao**, Shenzhen (CN); **Tianhang Ma**, Shenzhen (CN)

(73) Assignee: **Anker Innovations Technology Co., Ltd.**, Changsha (CN)

(**) Term: **15 Years**

(21) Appl. No.: **29/947,332**

(22) Filed: **Jun. 14, 2024**

(30) **Foreign Application Priority Data**

Dec. 15, 2023 (CN) 202330828738.7

(51) LOC (15) Cl. **15-05**

(52) U.S. Cl.

USPC **D32/23**

(58) **Field of Classification Search**

(57) **CLAIM**

The ornamental design for a robotic cleaner as shown and described.

DESCRIPTION

FIG. 1 is a front top perspective view of a robotic cleaner showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the robotic cleaner that form no part of the claimed design.

1 Claim, 8 Drawing Sheets
